MEANS FOR DRILLING HOLES IN ROCK
FORMATION AT OR BELOW THE
EARTH'S SURFACE

Howard L. Foster, Detroit, Mich.

Application July 30, 1949, Serial No. 107,808

4 Claims. (Cl. 255—72)

1

This invention relates to a means for drilling holes in rock formation at or below the earth's surface and it is to be understood as being connected with apparatus for rotating the drill to form a core, means being provided to break the core at successive intervals as the drilling proceeds.

These and other objects and features of the invention are hereinafter more fully described and claimed and apparatus embodying my invention is shown in the accompanying drawing in which—

Fig. 1 is a longitudinal section of the apparatus.

Fig. 2 is a cross section on an enlarged scale of the apparatus taken on line 2—2 of Fig. 1.

Fig. 3 is a longitudinal section showing an alternative apparatus.

Fig. 4 is a fragmentary longitudinal section of another variation.

Heretofore in hard rock formation it has been necessary to cease drilling after a certain length of core has been formed and then to break the formed core to permit removal from the hole, either by pulling or by applying torsional strain through rotation of the drill pipe, each of which operations may result in breakage of equipment and a costly fishing job. The elastic properties of various rock formations such as limestone, granite, sandstone and the like are available in literature or may be determined from tests.

This invention makes use of those properties known as the modulus of elasticity, the modulus of rupture in bending and the shearing strength.

The principal feature of my invention resides in the means for exerting a transverse pressure on the rock core within the drill whereby bending stresses are set up at the base of the core and, when the said stresses exceed the modulus of rupture, the core is caused to break off automatically as drilling progresses.

The device according to my invention involves a barrel 1 of cylindrical form having a core bit 1a at its lower end and the upper end is threaded to a member 2 which is internally threaded as indicated at 3 to receive the threaded end of an operating or rotating element not shown in the drawing. Intermediate the ends of the member 2 is a cylindrical chamber 4 having apertures 5 and 6 at an angle one to the other and opening to the cylindrical portion at one end and opening at the other end to the barrel. The lower portion 7 of the member 2 has a longitudinal recess 8 and a longitudinal recess 9 axially aligned with an opening to the lower end of the recess

2

8 and of less diameter than the diameter of the recess 8. In the recess 8 is a ball 10 engaging the inclined seat 11. A pin 12 having a threaded end 13, extends transversely of the longitudinal recess 8 to retain the ball within the recess 8 and limit the extent of movement of the ball on reciprocation of the drill. A barrel 14 is in threaded relation at its upper end with the threaded end of the lower portion of the member 2. The barrel 14 is within the tubular element 1 and has a downwardly and outwardly inclined eccentrically positioned lug 15, the inner face of which has a portion parallel with and spaced from the opposite side of element 14 a distance approximately equal to the diameter of the core 16 being formed in the drilling operation. The longitudinal axis of the lug and inner wall of element 14 coincides with the axis of the portion 16a of the core when the parts are in the position shown in Fig. 2. Lug 15 has a flat top surface arranged substantially normal to the longitudinal axis of element 14, and is adapted to support a severed or broken core thereon.

As the drilling proceeds the upper end of the core engages the inclined face 15a of the lug 15 which exerts a lateral pressure thereon. The inner diameter of the bit 1a which forms the core 16 is of less diameter than the interior diameter of the barrel 14. The latter has an upwardly and inwardly inclined face 18 on one side opposite to and spaced above the lug 15 for recentering the core. Furthermore the distance between face 18 and the top of lug 15 is at least slightly greater than the length of the severed core 16a so that its lower end clears lug 15 before the upper end engages face 18. Thus, as the drilling proceeds, the upper end of the core engages the inclined face 15a of the lug 15 and breaks off the core as indicated at 16b. Upon further drilling the broken off core is offset from the new core being formed and is pushed upwardly into the barrel 14, as indicated at 16a, while compressing the spring 17 attached to the barrel 14. Said spring is preferably a leaf spring of exterior convex form as shown in Fig. 2 and extends longitudinally of the element 14, being suitably secured thereto, preferably at its lower end, and arranged so as to be above lug 15. When the bottom of portion 16a reaches slightly above the top of lug 15 it is pushed laterally by the spring 17 so that all portions 16a above the lug 15 are supported by the lug. Any broken-off portion 16 is retained within the barrel 14 by the customary core catcher 20, but it is noted that that is the full extent of the load upon the

core catcher, so that on withdrawal of element 14 from the drilled hole the severed cores can't drop out.

As the drilling proceeds a number of the portions 16a are formed and, when the barrel 14 is practically filled with the severed portions 16a, the drill is removed from the hole and the broken portions are easily recovered from the barrel 14.

In the alternative form of the invention shown in Fig. 3 the member 2a corresponds to the member 2 shown in Fig. 1 and has passageways 5a and 6a corresponding to the passageways 5 and 6 of Fig. 1 but the threaded element 7a, corresponding to the element 7 of Fig. 1, is separated from the body 2a by ball bearing elements 19. The barrel 14a of Fig. 3 is a duplicate of the tubular element 14 of Fig. 1 and has the same functions.

In either form of the invention the wall of the barrel 14 or 14a is supported from deflection by the spaced reaction lugs 21 (Figs. 1 and 2) attached to the barrel 14 opposite the lug 15 which is subjected to lateral pressure in breaking the end of the core from the rock formation. As the barrel 14 or 14a becomes filled with core sections the drill is removed and the core sections recovered.

It is to be understood that in the form of my invention shown in Fig. 1, the lateral pressure exerted on the formed core by the rotating eccentric lug 15 is in a constantly changing radial direction and causes continuous reversals of stress in the rock core thus utilizing the lower value of the modulus of rupture in bending under conditions of stress reversal. In the form of my invention shown in Fig. 3 the barrel 14a does not rotate due to interposition of the ball bearing 19 and the lateral pressure applied by the lug 15 is in a constant direction, the barrel 14a being utilized as a floating core barrel.

It is also to be understood that where core contamination by the drilling fluid is of no consequence, the barrel 14 may be omitted as in Fig. 4 and the lug 15 attached to the tubular member 14 without departing from the spirit and scope of my invention.

It is believed obvious from the drawing and foregoing description that the various features and objects of the invention are attained by the functional character and relationship of parts as hereinbefore described.

Having thus briefly described my invention, its utility and mode of operation, what I claim and desire to secure by Letters Patent of the United States is:

1. A drill for the purpose described comprising a tubular member connected at one end with apparatus for rotation thereof, a core bit at the opposite end, a lug on the inner face of one side of the tubular member, said lug having a top supporting surface and a downwardly and outwardly inclined face engageable by one side of the upper end of the core whereby, as the drilling proceeds, an end of the core is broken from the body and the broken portion is moved upwardly within the tubular member, and resilient means upon the inner surface of said tubular

member positioned above said lug engageable with said broken portion for laterally positioning the same upon said lug.

2. A drill for the purpose described comprising a tubular member connected at one end with apparatus for rotating the same, a core bit at the opposite end, a lug on the inner face of one side of the tubular member, said lug having a downwardly and outwardly inclined face engageable with one side of the upper end of the core whereby, as the drilling proceeds, the core is broken and the broken portion positioned with its longitudinal axis offset relative to the axis of the core being formed, and resilient means on the inner wall of said tubular member above said lug engageable with the broken core for re-aligning the broken portion of the core with the longitudinal axis of the core being formed whereby the severed portions of the core are supported upon said lug.

3. A drill for the purpose described comprising a cylindrical member of tubular form connectable at one end with apparatus for rotating the same, a ringlike core bit at the opposite end, means joined to and projecting within the cylindrical member for breaking a portion of the core from the body thereof, whereby as the drilling proceeds, the tubular member becomes filled with the severed portions, and resilient means upon the interior of said member positioned above said first means for laterally projecting said broken portion of the core onto said first means in supported relation.

4. In a core drill, a tubular member for receiving a core, a core bit upon the end of said tubular member, a lug on the inner face of one side of the tubular member, said lug having a top horizontally arranged supporting surface and a downwardly and outwardly inclined face engageable with one side of the upper end of the core as it is moved upwardly within said tubular member whereby, as the drilling proceeds, the core is broken and the broken portion positioned with its longitudinal axis offset relative to the axis of the core being formed, and resilient means on the inner wall of said tubular member above said lug engageable with the broken core for re-aligning the broken portion of the core with the longitudinal axis of the core being formed, whereby the severed portions of the core are supported on said lug.
